SIGHT TESTING DEVICE

John F. Kothman, Minneapolis, Minn., assignor
of one-half to F. T. Persinger

Application January 6, 1936, Serial No. 57,831

9 Claims. (Cl. 88—20)

The invention relates to improvements in sight testing apparatus and more particularly to an electrically illuminated cabinet which may be used at a point near to the person whose sight is being tested, at a distance from 12—20 inches rather than at a distance of from 10—20 feet as in charts or other eye testing devices now in common use.

The general object of the invention is to provide means to hold and combine test cards, charts, etc. necessary to the optical profession in a convenient, neat and properly illuminated cabinet which can be worked with any near point subjective test.

According to my invention, a suitably illuminated cabinet is adapted to be rotatably suspended from a bracket or the like, so that a series of different faces having different forms of sight testing charts or the like thereon may be displayed at the will of the operator.

At one of the faces there is displayed a movable chart which is in the form of a roll and is adapted to be conveyed past a suitable opening or window in the face of the cabinet, the chart being manually movable over the rolls and being suitably supported so that a smooth surface is presented. The cabinet contains an electric light which is carried by a casing removable from the cabinet and adapted to support all the working parts.

The invention will be more readily understood by reference to the accompanying illustrative drawings in which:

Fig. 1 is a vertical sectional view of the sight testing cabinet certain parts being shown separated;

Fig. 2 is a front elevation of the working parts of the apparatus together with the casing carrying the same all removed from the cabinet;

Fig. 3 is a top plan view of the same;

Fig. 4 is a detailed view of the movable chart;

Fig. 5 is a perspective view of the cabinet on a reduced scale with the two faces thereof visible;

Fig. 6 is a perspective view of the same from a different angle and displaying the other two faces;

Fig. 7 is a vertical sectional view through the cabinet, the view being taken on line 7—7 of Fig. 5;

Fig. 8 is a horizontal sectional view on line 8—8 of Fig. 7; and—

Fig. 9 is a perspective view of the removable metal bracket shown in Fig. 2, the working parts being removed therefrom.

Referring more in detail to the drawings, the reference numeral 20 denotes a cabinet of box-

like construction and which may be of the size indicated in Fig. 1. The box or cabinet is rotatably supported by a handle or like member 21 which is suitably journalled to the box so as to permit relative rotation between the two. The bracket 21 may be supported from above in any suitable manner so that on rotation of the box 20, a plurality of testing charts A, B, C and D, one on each face of the box may be successively displayed. In this manner, various forms of basic charts may be combined in a single instrumentality.

As shown, the testing device A includes a pair of colored panes 22, 23, one being ruby red and the other marine blue, these panes being mounted in grooves 24 in the wall of the casing. A slip of 15 paper 25 with a chart thereon is slipped in back of the panes and is removable. The chart may include a plurality of letters at the top, squares below the letters and beneath the squares suitable wording, as for example, the question "Are the 20 squares equally clear under each color?"

B designates a movable chart which is shown in detail in Fig. 4 and includes various forms of eye testing cards. The chart B is adapted to be moved before an opening in the wall of the cabinet in a manner to be more fully described hereinafter and all of the charts will be suitably illuminated by a lamp 26 mounted in the interior of the cabinet.

C designates a meridial dial with a pinhole 27. 30

D represents a chart having rows of letters of varying sizes.

One of the faces of the cabinet 20 is removable to expose the interior. As shown, this is the face carrying the contrasting panes and owing to the 35 removability of this face, the panes are accessible for removal or replacement either of the panes themselves or of the paper chart. The cover face 28 may be held in place by suitable screws 29.

Within the cabinet is a removable casing E 40 preferably of sheet metal or other suitable material. Upon the casing is a lamp stand 30. The casing may be secured upon the base of the cabinet by means of screws 31 which pass through the base of the lamp stand, the casing E being slotted or cut away centrally at 32 as indicated in Fig. 9, 45 permitting the screws to pass therethrough into the base of the cabinet. A conductor cord 33 also passes through the slot 32 and is provided with branch wires 34 which lead to a switch 35 50 suitably controlled by a knurled button 36 or the like. The casing E is provided with an upstanding wall 37 at one end of the base and with a pair of spaced upstanding lugs 38 at the other. 55

An opening 50 is provided in the wall 37 to permit the switch wires 34 to pass therethrough. Openings 39 are provided in the wall 37 and in the lugs 38 between which a pair of chart rolls 40 are mounted, one on each side of the lamp and substantially at the base of the cabinet. It will be noted that these rolls are below the level of the lamp itself and consequently do not obscure the vision or interfere with any of the charts with which the cabinet is equipped. On one end of each of the rolls is a gear wheel 41, these gear wheels being outside of the casing wall 37. A master gear wheel 42 meshes with both of the roller gears 41 and is adapted to actuate the rolls. As shown, the casing E is provided with an upstanding lug 43 formed integral therewith by utilizing the metal struck out and forming the slot 32. The master gear wheel 42 is held between the lug 43 and the rear wall 37, an opening 44 being formed in the wall 37 to receive the bearing of the gear wheel. The gear 42 is provided with a shaft projecting outwardly through the wall of the cabinet upon which is mounted a suitable knurled handle 46 whereby the rolls may be actuated and chart B moved past the open face of the cabinet. It will be noted that the casing E is likewise provided with guide members formed integral therewith. The chart B is guided over the top member 47 and front members 48 which hold the chart taut in front of the opening in the outer cabinet.

It will be noted by referring particularly to Fig. 2 that the lamp, movable chart and all working parts are mounted in the single casing E which is adapted to be detachably secured in place, simply by adjusting the screws 31 passing through the base of the lamp stand. Thus it will be seen that the apparatus combines simplicity and economy.

Among the characteristic features of the invention I may mention the following:

- The working parts are removable.
- The working parts can be assembled independent of the cabinet.
- The working parts can be inserted in the cabinet and fastened to the bottom thereof merely by two screws passing through the light socket.
- The means for conveying the movable chart B before the opening is accomplished by the use of three cog wheels in proper mesh, the center cog wheel having a hub or shaft which passes through the side of the case and which is provided with a knurled knob fastened to the shaft by which it may be turned to the right or left at the operator's will, causing the other two cog wheels to turn in opposite directions.
- The band of charts is so fastened to the shaft of the two outer cog wheels that the same is wound on and off the shaft in unison which carries the charts before the opening in the cabinet, all springs, pulleys, belts and like complicated mechanism being eliminated.
- The apparatus includes two colored pieces of glass to be used at the near point, one being ruby red and the other marine blue, these features being important in completing the near point infinity technique test.
- The instrument contains the meridial dial and pin hole which are also important to near point subjective tests.
- The apparatus includes the Snelling near point chart which may be used in ordinary room light without turning out the light from the instrument.

Among the tests which may be employed with the present apparatus are:

1. The luminous near point infinity technique test.
2. All near point subjective near point tests known to optical science can be correctly made.
3. A full ametropic measurement can be obtained.
4. Latent hyperopia is readily ascertained.
5. Manifest hyperopia can be determined.
6. The reserve accommodation and amplitude can be measured.
7. All phoria and ductions can be found.
8. Infinity corrections can be written from the findings in connection with the near point infinity technique.

9. Suggestions for orthoptic treatment made plain by use of the instrument and the various techniques.

The invention has been described in detail for the purpose of illustration but it will be obvious that it may be varied without departing from the spirit of the invention.

I claim:

1. A sight testing apparatus comprising a cabinet having an opening on one face thereof, a movable test chart adapted to be manually moved past said opening, an electric lamp mounted at the base of said cabinet and adapted to illuminate said chart, a pair of spaced rolls for actuating said chart mounted one on one side and the other on the other side of said lamp near the base of said cabinet, said rolls having gear wheels at the ends thereof, a master gear for actuating both of the rolls and meshing with the gears at the ends of the rolls, and a removable casing carrying all the working parts, said casing including a single upstanding side wall and a pair of parallel guide members for said chart projecting from said side wall, one extending along the top and the other along the bottom of said opening.

2. A sight testing apparatus comprising a cabinet having an opening on one face thereof, a movable test chart adapted to be manually moved past said opening, an electric lamp mounted at the base of said cabinet and adapted to illuminate said chart, a pair of spaced rolls for actuating said chart mounted one on one side and the other on the other side of said lamp near the base of said cabinet, said rolls having gear wheels at the ends thereof, a master gear for actuating both of the rolls and meshing with the gears at the ends of the rolls, a removable casing carrying all the working parts, said casing having a base provided with a central slot parallel with the rolls to permit passage of a conductor cord for supplying current to the lamp, and an upstanding tab struck from said central slot for mounting said master gear.

3. A sight testing apparatus comprising a cabinet having an opening on one face thereof, a movable test chart adapted to be manually moved past said opening, an electric lamp mounted at the base of said cabinet and adapted to illuminate said chart, a pair of spaced rolls for actuating said chart mounted one on one side and the other on the other side of said lamp near the base of said cabinet, said rolls having gear wheels at the ends thereof, a master gear for actuating both of the rolls and meshing with the gears at the ends of the rolls, a removable skeleton casing carrying all the working parts, said casing including a base upon which the lamp socket is mounted, an upstanding wall, spaced guide arms for said chart projecting from said wall, and a

pair of upstanding tabs opposite said wall, said rolls being supported between said wall and said tabs on opposite sides of said lamp socket.

4. A sight testing device for use in making subjective tests comprising a cabinet having window openings in a plurality of faces thereof, test charts mounted in said openings, a removable skeleton casing mounted in said cabinet, said casing including a base, an upstanding wall at one side of the base, a pair of spaced upstanding tabs at the opposite side of the base, a plurality of vertically spaced horizontal guide arms extending from said upstanding wall, one of said guide arms disposed adjacent the upper edge and another disposed adjacent the lower edge of one of said window openings when said casing is in position in said cabinet, rollers journalled between said upstanding tabs and the upstanding wall of said casing, a movable chart trained over said guide arms to be exposed through said last-mentioned window and having its ends wound on said rollers, and a lamp mounted on the base of said removable casing positioned to illuminate said window openings.

5. As an article of manufacture for use in making subjective tests of the eyes, a revolvable cabinet, window openings in the vertical faces of said cabinet, a pair of contrastingly colored panes, one red and the other blue mounted in one of said window openings, a chart behind said panes, a dial and pinhole chart mounted in another of said window openings, a removable skeleton casing mounted in said cabinet, said casing including a base, an upstanding wall at one side of the base, a pair of spaced upstanding tabs at the opposite side of the base, a plurality of vertically spaced horizontal guide arms extending from said upstanding wall, one of said guide arms disposed adjacent the upper edge and another disposed adjacent the lower edge of one of said window openings when said casing is in position in said cabinet, rollers journalled between said upstanding tabs and the upstanding wall of said casing, a movable chart trained over said guide arms to be exposed through said last-mentioned window and connected at opposite ends to said rollers, and a lamp mounted on the base of said removable casing positioned to illuminate all of said window openings.

6. As an article of manufacture for use in making subjective tests of the eyes, a polygonal cabinet having window openings in a plurality of vertical faces thereof, a pair of contrastingly colored transparent panes, one red and the other blue mounted in one of said openings, a chart behind said panes, a dial and pinhole chart mounted in another of said openings, a letter chart mounted in another of said openings, a movable chart in the form of a web arranged to be viewed through another of said openings, a skeleton casing for supporting said movable chart, said casing providing a base having spaced upstanding tabs at one edge thereof and an upstanding wall at the opposite edge thereof, ver-

tically spaced guide arms for said movable chart projecting from said wall one above and one below said last-mentioned window, rollers for operating said movable chart journalled between said tabs and said wall, and a lamp mounted between said rollers, said lamp serving to illuminate all of said window openings.

7. As an article of manufacture for use in making subjective tests of the eyes, a polygonal cabinet having window openings in a plurality of vertical faces thereof, a pair of contrastingly colored transparent panes, one red and the other blue mounted in one of said openings, a chart behind said panes, a dial and pinhole chart mounted in another of said openings, a skeleton casing mounted in said cabinet, a movable test chart carried by said casing visible through another of said window openings, rollers journalled in said casing, said chart being in the form of a web having its ends wound on said rollers, and a lamp mounted in said casing in a position to illuminate the window openings.

8. A sight testing device for use in making subjective tests comprising a cabinet having window openings in a plurality of faces thereof, test charts mounted in said openings, a removable skeleton casing mounted in said cabinet, said casing including a base, an upstanding wall at one side of the base, a pair of spaced upstanding tabs at the opposite side of the base, a plurality of vertically spaced horizontal guide arms extending from said upstanding wall, one of said guide arms disposed adjacent the upper edge and another disposed adjacent the lower edge of one of said window openings when said casing is in position in said cabinet, rollers journalled between said upstanding tabs and the upstanding wall of said casing, a movable chart trained over said guide arms to be exposed through said last-mentioned window and having its ends wound on said rollers, a lamp mounted on the base of said removable casing positioned to illuminate said window openings, and means for driving said rollers in unison.

9. As an article of manufacture for use in making subjective tests of the eyes, a polygonal cabinet having window openings in a plurality of vertical faces thereof, a source of illumination for the interior of the cabinet, a pair of contrastingly colored transparent panes, one red and the other blue mounted in one of said openings, a chart behind said panes, a dial and pinhole chart mounted in another of said openings, a letter chart mounted in another of said openings, spaced rollers mounted in said cabinet, and a movable test chart visible through another of said window openings, said chart being in the form of a web having a plurality of sight testing means thereon and having its ends wound on said rollers, and means for driving said rollers to selectively bring the sight testing means on said movable chart into said last-mentioned window.

JOHN F. KOTHMAN.
